(57) **ABSTRACT**

A new variety of *Gentiana L.* plant (Japanese gentian) which has a color of inner side of lobes which is light purple (N80D on The R.H.S. Colour Chart) and a stem length of 77.9 cm on average.

4 Drawing Sheets

1

Common name: Japanese gentian.
Botanical classification: *Gentiana L. hybrid*.
Variety denomination: 'Ashiro 29-2059'.

BACKGROUND OF THE NEW VARIETY

The present invention relates to a new and distinct variety of Japanese gentian, *Gentiana L.*, which has been given the variety denomination 'Ashiro 29-2059'.

This new gentian has a color of inner side of lobes which is light purple (N80D on The R.H.S. Colour Chart) and a stem length of 77.9 cm on average. It is adapted for use as cut flowers or pot flowers.

ORIGIN OF THE VARIETY

The variety resulted from a multiple-step cross-breeding program starting from a group of unpatented varieties. The ancestor varieties were unpatented strains owned by the applicant, having the company-internal names: '17INP' which belongs to the species *Gentiana triflora*, and '25-322-R1', '26-904', '12-320-1', '14-526-2', '11-24-1', '11-192-1', '13SH', '10-76', '6-62', '12-186-1', '12-212-1', '25-817', '17SUP', and '8-130SP6A1', which belong to the species *Gentiana scabra*. Group crosses and/or self-crosses with a single individual were performed. The program had seven steps, as shown in the map of FIG. 6, which also indicates the company-internal names of the intermediary, unpatented strains. At each step, the individuals with good plant and flower shape were selected. The corresponding species identification is (((scabra x (scabra x triflora))x scabra))x((scabra x triflora)x scabra)).

With respect to the direct parents '28-2012Co-1e' and '27-836-53', the instant variety 'Ashiro 29-2059' has a triploid and double-flowered flower type, whereas '28-2012Co-1e' has tetraploid and double-flowered flower type, and '27-836-53' has diploid and single-flowered flower type.

2

The multiple-step cross-breeding program was performed over multiple growing seasons up to 2018; in September 2018, selection of the variety was performed. We asexually reproduced the variety by vegetative reproduction through 5 cuttings, tissue culturing via lateral bud culture, and in October 2020, the new variety was found to be stable and asexually reproduced true to type in successive generations. The variety was developed and propagated in Iwate, Japan.

The variety can be propagated by cutting (optimal timing 10 is mid-February) and/or tissue culturing via lateral bud culture.

Cultivation of the variety does not require particular conditions. Maintenance and storage method of the plant material can be by tissue culture via lateral bud culture.

15 The variety is adapted for use as cut flowers or pot flowers.

SUMMARY OF THE VARIETY

20 The variety is distinguished by the color of inner side of lobes being light purple (N80D on The R.H.S. Colour Chart) and by its stem length of 77.9 cm on average, as compared to 'Lovely Ashiro' variety whose color of inner side of lobes is pale purple (N75B on The R.H.S. Colour Chart) and whose stem length is 110.1 cm on average. 'Lovely Ashiro' is unpatented.

25 A comparison with 'Lovely Ashiro' variety is presented as follows in Table 1:

TABLE 1

	'Lovely Ashiro'	'Ashiro 29-2059'
Color of inner side of lobes	Pale purple (N75B on the RHS Colour Chart)	light purple (N80D on the RHS Colour Chart)
Stem length	110.1 cm	77.9 cm

Additional distinguishing characteristics of the 'Ashiro 29-2059' plant are the five-six (5.8 on average) lobes of the paracorolla.

BRIEF DESCRIPTION OF THE DRAWINGS

In the accompanying drawings, which are as nearly true as is reasonable possible to make in a color illustration of this type:

FIG. 1 is a color photograph showing the 'Ashiro 29-2059' plant as grown in a culturing bed;

FIG. 2 is a color photograph showing flowers of the 'Ashiro 29-2059' plant;

FIG. 3 is a color photograph showing flowering stages of flowers of the 'Ashiro 29-2059' plant;

FIG. 4 is a color photograph showing petals of flowers of the 'Ashiro 29-2059' plant;

FIG. 5 is another color photograph showing flowers of the 'Ashiro 29-2059' plant;

FIG. 6 is a map showing the steps of the cross-breeding program from which the variety was obtained.

Due to chemical and/or digital development, processing and printing, the plants or portions of plants depicted in the

photographs may or may not be precisely accurate, when compared to the actual botanical specimens.

DETAILED DESCRIPTION OF THE INVENTION

The plants in the botanical description below and shown in the Figures were grown in Iwate, Japan. The plants were collected in October 2020 at age 16 months.

Colors are given according to The 2015 R.H.S. Colour Chart.

BOTANICAL DESCRIPTION

TABLE 2

Length:	77.9 cm				(N77B on RHS Colour Chart)
Thickness (main flowering stem):	3.9 mm				double
Number of flowering stems per plant (average):	11.8	45	Flower		late October
Texture:	smooth				13 days
Color:	light yellow green (145B on RHS Colour Chart)		Corolla		8 days
Anthocyanin coloration at two thirds from base:	present	50			46.3 mm
Number of internodes longer than 5 mm (average):	23.4				18.0 mm
Length of internode in central third:	3.5 cm				campanulate
Side shoots:	present	55			33.2 mm
Number of side shoots with only one node (average):	1.3				strongly reflexed
Number of side shoots with more than one node (average):	13.2				entire
Length of side shoots (average):	50.2 cm				smooth
Diameter of side shoots (average):	2.6 mm	60			light purple (N80D on RHS Colour Chart)
Texture of side shoots:	smooth				light purple (N80D on RHS Colour Chart)
Color of side shoots:	light yellow green (145C on RHS Colour Chart)				28.7 mm
Position of longest leaf:	in central third	65			smooth
					light purple (76A on RHS Colour Chart)
					strong purple (77B on RHS Colour Chart)
					greyish purplish red (N77B on RHS Colour Chart)

TABLE 2-continued

Leaf	Length:	10.2 cm
	Leaf arrangement:	opposite leaf arrangement
5	Leaf attachment:	sessile
	Leaf apex:	acuminate
	Leaf margin:	entire
	Leaf base:	rounded
	Leaf texture (inner side):	smooth
	Leaf texture (outer side):	smooth
10	Leaf color (inner side):	moderate olive green (137A on RHS Colour Chart)
	Leaf color (outer side):	moderate yellow green (139D on RHS Colour Chart)
15	Leaf venation pattern:	parallel venation (five lines)
	Leaf venation color:	light yellow green (150D on RHS Colour Chart)
20	Width:	1.9 cm
	Shape:	narrow lanceolate
	Shape in cross section:	folded upwards
	Shape in longitudinal section:	concave
	Twisting:	present
	Number of conspicuous veins:	5
	Anthocyanin coloration:	present, dark greyish red (N186C on RHS Colour Chart)
25	Inflorescence:	Distribution of flowers: clustered
		Position of flowers: terminal and axillary
		Number of inflorescences per plant per season (average): 366.7
30	Plant:	Number of terminal flowers (average): 6.7
		Typical growth habit: erect
		Plant height (average): 77.9 cm
		Plant spread (average): 86.6 cm
		Plant shape: erect
35		Number of flowers per inflorescence: top: 6.7 others: 2.9
		Number of flowers at central flowering node (average): 2.9
		Number of flowering node: 7.5
		Shape of bud: oval
40	Flower bud (about 4 days before flowering):	Length of bud (average): 38.32 mm
		Diameter of bud (average): 13.54 mm

	Length of bud (average):	38.32 mm
	Diameter of bud (average):	13.54 mm
	Color of bud:	greyish purplish red (N77B on RHS Colour Chart)
45	Flower	
	Type:	double
	Time of flowering:	late October
	Flower longevity (potted plant):	13 days
	Flower longevity (cut flower):	8 days
	Corolla	
	Depth:	46.3 mm
50		
	Diameter at middle third:	18.0 mm
	Shape:	campanulate
	Diameter at top:	33.2 mm
	Curvature of lobes:	strongly reflexed
	Margin of lobes:	entire
	Texture of lobes:	smooth
55		
	Color of outer side of lobes:	light purple (N80D on RHS Colour Chart)
	Color of inner side of lobes:	light purple (N80D on RHS Colour Chart)
	Tube length (average):	28.7 mm
60		
	Tube texture:	smooth
	Color of inner side of tube:	light purple (76A on RHS Colour Chart)
	Color of upper part of inner side of tube:	strong purple (77B on RHS Colour Chart)
	Color of outer side of tube:	greyish purplish red (N77B on RHS Colour Chart)

TABLE 2-continued

Color of upper part of outer side of tube:	greyish purplish red (N77B on RHS Colour Chart)	5	Reproductive organs	Sepal color (outer side):	moderate yellow green (143D on the RHS Colour Chart)
Streaked pattern on outer side of tube:	present			Stamens and anther:	stamens are mutated into petals and there is no anther
Color of streaked pattern on outer side of tube:	greyish purplish red (N77B on RHS Colour Chart)	10		Pistil number:	1
Number of lobes:	at least 6			Pistil length (average):	35.9 mm
Length of lobes:	8.1 mm			Stigma (none)	
Width of lobes:	11.9 mm			Style (none)	
Shape of lobes:	broad triangular			Ovary color:	light yellow green (145C on RHS Colour Chart)
Shape of distal end of lobes:	acute			Roots	Root shape: fine and fibrous
Presence of secondary lobes:	present			Pedicel	No pedicel
Shape of secondary lobes:	acute			Peduncle	Peduncle length (average): 1.89 mm
Shape of secondary lobe apex:	acute	15			Peduncle diameter (average): 2.64 mm
Margin of secondary lobes:	entire				Peduncle texture: smooth
Length of secondary lobes (average):	3.8 mm				Peduncle color: light yellow green (145C on RHS Colour Chart)
Width of secondary lobes (average):	5.2 mm				
Texture of secondary lobes:	smooth	20			
Presence of paracorolla:	present				
Number of paracorolla lobes (average):	5.8				
Calyx					
Anthocyanin coloration:	present	25			
Length of tube:	14.1 mm				
Diameter of tube:	7.6 mm				
Shape of tube:	funnel-shaped				
Texture of tube (inner side):	smooth				
Texture of tube (outer side):	slightly wrinkled				
Shape of lobe:	narrow lanceolate				
Sepal					
Sepal number:	6	30			
Sepal lobe shape:	narrow lanceolate				
Sepal length (average):	28.9 mm				
Sepal width (average):	4.1 mm				
Sepal apex:	acute				
Sepal margin:	entire				
Sepal texture (inner side):	smooth				
Sepal texture (outer side):	smooth				
Sepal color (inner side):	moderate yellowish green (139B on the RHS Colour Chart)				

TABLE 2-continued

5	Reproductive organs	Sepal color (outer side):	moderate yellow green (143D on the RHS Colour Chart)
		Stamens and anther:	stamens are mutated into petals and there is no anther
		Pistil number:	1
		Pistil length (average):	35.9 mm
		Stigma (none)	
		Style (none)	
		Ovary color:	light yellow green (145C on RHS Colour Chart)
10		Roots	Root shape: fine and fibrous
		Pedicel	No pedicel
		Peduncle	Peduncle length (average): 1.89 mm
15			Peduncle diameter (average): 2.64 mm
			Peduncle texture: smooth
			Peduncle color: light yellow green (145C on RHS Colour Chart)

In the above chart, specific numbers correspond to average values.

Other features of the plant are as follows:

Disease resistance.—Normal resistance was observed for pests and diseases in Iwate, Japan, using pest control by chemical spraying for gentian.

Cold hardiness.—Strong, the variety can withstand winter in Iwate, Japan, including low temperatures of about -10° C. with abundant snow.

Heat tolerance.—Normal, the variety can withstand summer in Iwate, Japan, including high temperatures of about 35° C.

Flower fragrance.—Absent.

We claim:

1. A new and distinct variety of *Gentiana* plant named 35 'Ashiro 29-2059', substantially as described and illustrated herein.
